UNITED STATES PATENT OFFICE

150,145

DESIGN FOR A RADIO RECEIVER WITH TIMED AUTOMATIC STATION SELECTOR AND TUNER

John Lolli and Gene Papitto, Chicago Heights, Ill.

Application June 7, 1947, Serial No. 139,514

Term of patent 7 years

(Cl. D56—4)

To all whom it may concern:

Be it known that we, John Lolli and Gene Papitto, citizens of the United States, residing at Chicago Heights, in the county of Cook and State of Illinois, have invented a new, original, and ornamental Design for Radio Receiver With Timed Automatic Station Selector and Tuner, of which the following is a specification, reference being had to the accompanying drawings, forming part thereof.

Referring to the drawings:

Fig. 1 is a front elevational view of a radio receiver with timed automatic station selector and tuner, showing our new design;

Fig. 2 is a side elevational view, taken from the left side of Fig. 1;

Fig. 3 is a side elevational view, taken from the right end of Fig. 1; and

Fig. 4 is a rear elevational view.

We claim:

The ornamental design for a radio receiver with timed automatic station selector and tuner, as shown.

JOHN LOLLI.
GENE PAPITTO.
